CLAIM

The ornamental design for a versatile sink rack, as shown and described.

DESCRIPTION

FIG. 1 shows a perspective view of a versatile sink rack;

FIG. 2 shows a front view thereof;

FIG. 3 shows a rear view thereof;

FIG. 4 shows a right side view thereof;

FIG. 5 shows a left side view thereof;

FIG. 6 shows a top plan view thereof; and,

FIG. 7 shows a bottom plan view thereof.

The shade lines in the Figures show contour and not surface ornamentation.
